INVENTOR,
FREDERIC WAMBACK

BY

Richard B. Owen

ATTORNEY.

UNITED STATES PATENT OFFICE.

FREDERIC WAMBACK, OF GREENWICH, CONNECTICUT.

COMBINED MILK-BOTTLE HOLDER AND LOCK.

1,351,359.

Specification of Letters Patent. Patented Aug. 31, 1920.

Application filed May 8, 1919. Serial No. 295,554.

To all whom it may concern:

Be it known that I, FREDERIC WAMBACK, a citizen of the United States, residing at Greenwich, in the county of Fairfield and State of Connecticut, have invented certain new and useful Improvements in Combined Milk-Bottle Holders and Locks, of which the following is a specification.

The primary purpose of this invention is the provision of a device for receiving a bottle, jar or like container such as commonly used for the delivery of milk and which will secure the bottle against appropriation by an unauthorized party, since the device embodies locking means to engage and prevent removal of the bottle after the same has been properly placed in position except by the use of a proper key. Thus the consumer is reasonably assured against theft and the merchant is guarded against the loss of bottles because when the empty bottle is placed in the rack it cannot be removed therefrom except by one possessing a key for opening the locking mechanism, whereby the bottle may be released.

The drawing illustrates a preferred embodiment of the invention. However, it is to be understood that in adapting the same to meet different conditions, various changes in the form, proportion, and minor details of construction may be resorted to without departing from the nature of the invention as claimed hereinafter.

The drawing illustrates an adaptation of the invention and in the same,

Figure 1 is a vertical central section of a combined milk bottle holder and lock constructed in accordance with and embodying the essential features of the invention.

Fig. 2 is a vertical section on the line 2—2 of Fig. 1 looking to the left, as indicated by the arrow.

Fig. 3 is a horizontal section on the line 3—3 of Fig. 1 looking in the direction designated by the arrow.

Fig. 4 is a horizontal section on the line 4—4 of Fig. 1.

Corresponding and like parts are referred to in the following description and indicated in the several views of the drawing by like reference characters.

The device comprises a rack for receiving the bottle, or like form of container and locking means for securing the bottle when properly positioned in the rack. The rack comprises a holder in which the bottle is

placed and a brace for strengthening the holder. The holder may be of any construction and, as indicated, comprises a base 1 and opposite side arms 2 and 3. The base 1 and side arms 2 and 3 preferably constitute parts of a single metal strap which has its end portions bent in the same direction to form the side arms. An attaching bar 4 is disposed exterior to the side arm 2 and is in contact therewith and projects some distance below the base 1 and a strut 5 connects the lower end of the attaching bar with the outer end of the base 1. The upper end of the strut 5 has a portion underlapping the base 1 and secured thereto in any preferred way. A band 6 is secured at opposite points to the upper ends of the side arms 2 and 3 and the attaching bar 4 and has an inner flange 7 which serves as stiffening means and as a guard for gripping ring 8 which is disposed within the band 6 adjacent the flange 7 which overhangs the same.

The gripping ring 8 is adapted to be contracted to engage about the neck of the bottle 9 which is indicated by dotted lines in Figs. 1 and 2, thereby preventing withdrawal of the bottle so long as the gripping ring 8 is contracted. The gripping ring 8 is preferably of sectional formation and comprises two similar sections which are pivotally connected at 10, said pivot fastening passing through the flange 7 and being of such construction as to prevent the removal of the fastening. Each of the sections of the gripping ring 8 is of semi-circular form and is pivotally connected to one arm of a U-shaped lever 11 which is pivoted at 12 to a plate 13 fastened in any manner to the side arm 2 and upper portion of the attaching bar 4. The U-shaped levers 11 are pivoted intermediate of their ends and have the extremities of their lower arms overlapping and pivotally connected to one another and to a bar 14 by a suitable fastening 15. Vertical movement of the bar 14 rocks the U-shaped levers 11 in a manner to cause the extremities of their upper arms to approach one another or move apart with the result that the free ends of the sections comprising the gripping ring 8 are drawn together to contract the ring or moved apart to expand the said ring. The operating bar 14 is provided at its lower end with a rest 16 which engages the bottom of the bottle 9. A stud 17 projects rearwardly from the lower portion of the operating bar 14 and engages

the side arm 2, thereby preventing outward movement of the lower end of the bar 14 when pressure is exerted on the bottle 9 to depress the rest 16 and bar 14 to effect contraction of the locking ring 8 and operation of the lock mechanism.

A locking element 18 depends from the rest 16 and passes through an opening formed in the base 1 and is adapted to be engaged by means of a lock bolt 19 of a suitable lock mechanism mounted upon the rack and for convenience disposed beneath the base 1 and in the space inclosed by the lower portion of the attaching bar 4 and the strut 5. The lock mechanism is disposed within a suitable casing 20 and is adapted to be operated by means of a key 21, as indicated by dotted lines in Fig. 4. It is to be understood that the lock mechanism may be of any design so long as it co-operates with the locking element 18 to secure the gripping ring 8 in contracted position about the neck of the bottle 9, thereby preventing removal of such bottle until released by opening the lock by means of a proper key 21.

A bottle rack and lock constructed in accordance with this invention involves a relatively simple and light structure and may be readily attached to a wall, post or other support and is adapted to receive either a filled or an empty bottle. In this way the consumer is assured of safe delivery of the goods and the merchant is enabled to have the empty bottles safely returned, since neither the full nor the empty bottle may be removed from the rack when properly positioned therein except by the use of a proper key with which both the consumer and the merchant are possessed. It is assumed that the gripping ring 8 is expanded, hence the operating bar 14 and rest 16 are relatively elevated. A bottle 9 being placed in the holder passes through the opening encircled by the flange 7 and through the gripping ring 8 until its bottom comes in contact with the rest 16. Pressure is now exerted upon the bottle to effect a lowering of the rest 16 and operating bar 14 with the result that the locking element 18 is depressed and brought into locking engagement with the bolt 19 and made secure thereby. At the same time the levers 11 are rocked, thereby drawing the free ends of the gripping ring 8 together and contracting such gripping ring about the neck of the bottle 9 in a manner to prevent withdrawal of the bottle. It will thus be understood that the bottle is made secure both for the consumer and the merchant and either one may obtain the bottle by releasing the lock mechanism and drawing upward on the bottle to remove it from the holder, the sides of the bottle riding upon the gripping ring and expanding the same and setting the device for reception of the next bottle.

The foregoing description and the drawing have reference to what may be considered the preferred, or approved form of my invention. It is to be understood that I may make such changes in construction and arrangement and combination of parts, materials, dimensions, et cetera, as may prove expedient and fall within the scope of the appended claims.

Having thus fully described my invention, what I claim as new and desire to secure by Letters Patent is:—

1. A bottle rack comprising a base, arms extending upwardly from the base, an annular member connecting the upper ends of the arms and having an inner flange, an inclosed locking mechanism disposed below the base, contractile bottle gripping means located within the annular member just below the flange thereof, an operating bar having a bottle engaging rest at its lower end and having its upper end connected with the bottle gripping means and a locking element movable with the operating bar and adapted to pass through an opening in the bottom and co-operating with the locking element to secure the parts in locked position.

2. In a bottle rack, comprising a holder for receiving the bottle, oppositely disposed bottle gripping elements, an operating bar slidable within the holder, levers pivoted intermediate their ends and having pivot connection with the bottle gripping element and operating bar, a rest at the lower end of the operating bar to be engaged by the bottom of the bottle, a key operated locking mechanism disposed beneath the holder, and a locking element movable with the operating bar and adapted to be secured by said locking mechanism to prevent removal of the bottle when properly positioned in the holder.

3. In a bottle rack, including a holder for receiving the bottle, a contractile bottle gripping ring, U-shaped elements pivoted intermediate their ends and having corresponding ends connected with the free ends of the bottle gripping ring, an operating bar connected with the other ends of said elements and adapted to be actuated by the bottle, and a key operated locking mechanism for securing the bottle gripping ring in locked engagement.

4. A bottle rack, including a holder for receiving the bottle, a gripping ring comprising pivoted sections, co-operating U-shaped elements pivotally connected at corresponding ends to the free ends of the ring sections, an operating bar connected with the other ends of said elements for actuating the same and adapted to be operated by the bottle, and a key operated locking mechanism for securing the operating bar when the gripping ring is in locked engagement with the bottle.

5. A bottle rack, comprising a holder for

receiving the bottle, bracing means for the holder disposed beneath the bottle thereof and comprising an attaching bar and a strut, a key operated locking mechanism located in 5 the space formed between the attaching bar strut and bottom of the holder, bottle gripping means within the holder and operating means for the bottle gripping means adapted to be actuated by the bottle and having a

locking element passing through the bottom 10 of the holder and coöperating with the said locking mechanism.

In testimony whereof I affix my signature in presence of two witnesses.

FREDERIC WAMBACK.
